ELECTRON DISCHARGE DEVICE

Henry W. Parker, Toronto, Ontario, Canada, assignor to Rogers Radio Tubes, Limited, Toronto, Ontario, Canada, a corporation of Ontario, Canada

Application December 27, 1930, Serial No. 505,045

3 Claims. (Cl. 250—27.5)

My invention pertains in general to electron discharge devices of the type known as thermionic tubes which employ a screening grid in addition to the control grid.

The function of the screen grid in a thermionic tube as is well known is, briefly, to improve the conductance and hence the efficiency of the tube through eliminating as nearly as possible electrostatic coupling between the control grid and the anode of the tube and space charge effect between the cathode and anode. The screen grid, to function efficiently as an electrostatic shield, must be composed of many turns of wire disposed with a relatively small space between adjacent turns, or of a screen having a fine mesh. Such construction, however, produces an undesirable effect in that the projected area of such a grid with respect to the anode is relatively large and hence the screen intercepts a considerable portion of the electrons flowing to the anode to, in effect, reduce the gain achieved by the electrostatic screening. The ideal screen, of course, would be one which, while functioning to eliminate the space charge effect, offered no impediment whatever to the flow of electrons between the cathode and the anode.

An object of my invention is to provide a screen grid for thermionic tubes which in a great degree approaches the above noted characteristics of an ideal screen.

Another object of my invention comprises producing a screen grid whereby the desired electrostatic screening effect may be obtained with minimum interception of the electron stream.

A still further object of my invention comprises producing a screen grid whereby the conductance of the tube is increased to thus increase the overall efficiency of the tube.

I accomplish all of the above noted desirable features by providing a screen grid in the form of two or more grids, each having a relatively coarse mesh and all electrically connected to a common terminal.

In the figures accompanying and forming a part of this specification and in which like reference numerals designate corresponding parts throughout:

Fig. 1 is a partially sectioned elevation of a thermionic tube provided with my improved screen grid and with the enclosing envelope omitted.

Fig. 2 is a sectional plan view of the same taken on the line 2—2 of Fig. 1.

Referring now particularly to the figures which illustrate one form of screen grid tube incorpo-

rating my novel screen grid. The press 1 supports the usual anode 12 concentrically located within which is the cathode 2 which I have arbitrarily chosen to illustrate as of the indirect heated type employing a heating wire 3. Surrounding the cathode 2 there is provided the usual control grid 4, supported by standards 9 and 10, and provided with the usual terminal 14.

My improved screen grid comprises two grids of relatively coarse mesh as shown, concentrically disposed with respect to each other and maintained between the control grid 4 and the anode 12 as illustrated. The screen grid I have chosen to illustrate comprises two helices of wire which are spot welded or otherwise attached to supports as 5 and 6 and these supports are shown connected together, thus electrically connecting the two grids, by conductors 11. The grids thus united are supported in the press by the standards 7 and 8 one of which 7, serves as a terminal therefor and are maintained in relative position with respect to the other elements of the tube by the perforated mica disk 15 which is supported by the cathode 2.

It will be noted that the mesh of these two screen grids is considerably coarser than that of the control grid 4 and that they therefore produce a relatively smaller projected area on the anode and hence intercept only a small portion of the electron stream passing from the cathode to the anode. The two grids taken jointly thus present a smaller obstruction to the electron space current flow to the anode than would be caused by a single grid having a much closer mesh and consequently the same electrostatic screening capacity. The effect of one grid upon another is, so far as the amplification constant of the tube is concerned, one of multiplication. For instance, if a single grid is closely wound to give an amplification constant of 64, then a double grid with much wider spacing between the turns, each having a Mu of 8, will give the same amplification constant because the product of the Mu of one screen by that of the other is equal to 8×8 , or 64.

In other words, while a single screen of coarse mesh would produce an amplification lower than that desired, a plurality of such screens serves to multiply the amplification constant to the desired value. Thus by the use of two or more relatively coarse screens electrically interconnected which offer a minimum obstruction to the electron flow, I am able to produce a thermionic tube having an increased efficiency through increased anode conductance, and

still maintain the desired degree of electrostatic screening and high amplification constant.

It will be obvious from the foregoing that my improved screen increases the anode conductance and maintains a high amplification constant to achieve a high over-all tube efficiency.

In experimental tubes which I have constructed, I have been able, through the use of my improved screen grid, to build tubes in which the screen intercepts only about one-third of the electron stream intercepted by screens now common in the art, to increase in a marked manner the anode conductance, while maintaining the desired degree of electrostatic screening and high amplification constant.

While I have chosen to illustrate my improved screen grid as used in conjunction with a thermionic tube utilizing only an inner screen instead of both an inner and outer screen, it is of course obvious that my screen grid will function with both types of construction equally well.

Having thus completely described and disclosed my invention, what I claim as new and desire to secure by Letters Patent of the United States is as follows:

1. In an electron discharge device, a sealed container, a cathode, an anode, and a control electrode within said container, and an electrostatic screen composed of a plurality of separate

screening members each including a conductor disposed in the form of a helix, the open area of which is considerably greater than the solid area thereof, completely surrounding said cathode, said members being electrically interconnected and positioned one within the other between said control electrode and said anode. 5

2. In an electron discharge device, a sealed container, a cathode, an anode, and a mesh control electrode within said container, and an electrostatic screen composed of a plurality of screens of relatively coarser mesh than that of said control electrode, each encircling said cathode, concentrically disposed with respect to each other, electrically interconnected and maintained between said control electrode and said anode. 10

3. In an electron discharge device, a sealed container, a plurality of electrodes including a cathode, an anode, and a control electrode within said container, and an electrostatic screen composed of a plurality of separate screening members each including a conductor disposed in the form of a helix, the open area of which is considerably greater than the solid area thereof, surrounding said cathode, said members being electrically connected and positioned one within the other between said control electrode and said anode. 20 25
